ROTARY FINISHING PRESS

David Gessner, Worcester, Mass.

Application September 12, 1938, Serial No. 229,497

6 Claims. (Cl. 38—2)

This invention relates to the finishing of woolen and worsted cloth, and relates more particularly to rotary presses used for ironing and pressing long pieces of cloth.

5 It is the general object of my invention to provide an improved construction in rotary finishing presses, by which increased production and a superior finish may be attained.

To the attainment of this general object, important features of my invention relate to improved means for applying, adjusting and equalizing the ironing pressure, and to the provision of simplified and effective actuating and control mechanism for said machine.

15 My invention further relates to arrangements and combinations of parts which will be herein-after described and more particularly pointed out in the appended claims.

A preferred form of the invention is shown 20 in the drawings, in which

Fig. 1 is a front elevation of my improved rotary press;

Fig. 2 is a plan view of certain driving mechanism, looking in the direction of the arrow 2 25 in Fig. 1;

Fig. 3 is a partial end elevation, looking in the direction of the arrow 3 in Fig. 2;

Fig. 4 is a partial rear elevation of the machine;

30 Figs. 5, 6 and 7 are detail end elevations, looking in the directions of the arrows 5, 6 and 7 in Fig. 4;

Fig. 8 is an end elevation, looking in the direction of the arrow 8 in Fig. 1;

35 Fig. 9 is a sectional front elevation, taken along the line 9—9 in Fig. 8;

Fig. 10 is a partial plan view, looking in the direction of the arrow 10 in Fig. 8;

Fig. 11 is a partial front elevation, looking in 40 the direction of the arrow 11 in Fig. 10; and

Fig. 12 is a partial sectional view, taken along the line 12—12 in Fig. 10.

The travel of the cloth and the general operation of the machine is well shown in Fig. 9, where 45 it appears that the cloth C is directed by guide-rolls 20, 21, 22 and 23 along paths adjacent rotary brushes 24 and 25 by which the two faces of the cloth are effectively brushed. Any usual friction devices may be provided for retarding the guide-rolls 21 and 23 which receive the pull of the brushes.

The cloth then passes under a guide-roll 26, over a rotatably mounted stretch roll 27, and under a guide-roll 28, from which point it passes 50 around the main cylinder 30 and between the

pressure beds or ironing members 31 and 32. The cloth then passes around a guide-roll 33 to any usual delivery mechanism.

The ironing member 31 is pivotally connected by links 35 (Fig. 10) to the upper ends of two actuating levers 36, and the member 32 is similarly connected by links 35^a to the upper ends of two actuating levers 36^a. Each lever 36 or 36^a is mounted on a floating pivot stud 37 (Figs. 8 and 9) supported by fixed brackets 38 and slide-able on the horizontal top surfaces thereof.

Each pivot stud 37 extends through a rod head 40 (Fig. 9), and the rod heads for a pair of associated but oppositely disposed levers 36—36^a are connected by a cross rod 42 having right and left- 15 hand screw threads for the rod heads. A worm wheel 43 is fixed on each rod 42. By rotating either one of the rods 42, the space between the pivot studs 37 for a pair of associated levers 36—36^a at opposite sides of the machine can be 20 varied and adjusted. The pivot studs are nevertheless free to slide toward and from the cylinder 39 on the brackets 38. Springs 44 (Fig. 9) on the ends of the brackets 38 engage the pivot studs 37 and tend to move them yieldingly apart, 25 thus taking up any lost motion.

The lower end of each lever 36 is connected by a link 45 (Fig. 9) to one of two rocking members 46, fixed on a cross shaft 47. The lower end of each lever 36^a is connected to the sec- 30 ond arm of one of the rocking members 46 through a link 48 which includes a spring 49, held under heavy compression but capable of further compression to relieve excess pressure.

The springs 49 act as safety devices to limit 35 the pressure of the ironing members 31 and 32 against the main cylinder 39 and against the cloth passing around said cylinder. The degree of compression of the springs 49 may be adjusted by nuts 50.

The crank arms 51 on the shaft 47 is connected by a link 52 (Fig. 8) to a crank arm 53 on a cross shaft 54. The shaft 54 is given partial rotation only in alternate directions to apply and relieve ironing pressure, as will be hereinafter 45 described.

Driving mechanism and connections

I will now describe the driving mechanism of my improved machine. The main drive is 50 through a drive shaft 60 (Figs. 1 and 2), continuously rotated from any suitable source of power. The shaft 60 is connected through a clutch 61 to a driven shaft 62, and a handle 63 is provided for moving the clutch.

The shaft 62 is provided with a sprocket 64 which drives a chain 65 which in turn engages sprockets 66 and 67 associated with the brushes 24 and 25, all as shown in Figs. 1 and 2. By 5 these connections, the brushes 24 and 25 are continuously rotated but in opposite directions.

The shaft 62 is also connected by chains 70 (Fig. 1) to sprockets 71 on a countershaft 72 (Fig. 2) and the countershaft 72 is connected 10 through sprockets 73 (Fig. 3), chain 74 and sprockets 75 to the shaft 76 which supports and drives the main cylinder 30. The shaft 76 and a corresponding rear journal 77 (Fig. 8) are rotatable in bearings 78 on the front and back frame 15 members 79 and 80, which frame members are rigidly connected by one or more girders 81 (Figs. 3 and 8).

In Fig. 1 I have also shown a belt tightener for 20 the chains 74, which tightener comprises a sprocket 83 mounted on a lever 84 and yieldingly pressed against the chains by a weight 85. By shifting the clutch lever 63, the main cylinder 30 and brushes 24 and 25 may thus be simultaneously started and stopped.

25

Pressure-applying mechanism

I have provided separate power mechanism for 30 applying and relieving the pressure on the ironing members 31 and 32. For this purpose, I provide a motor M (Figs. 4 and 5) connected through suitable gearing to drive a cross shaft 90 having a pinion 91 mounted thereon and engaging a gear 92 rotatable on an intermediate shaft or stud 93. A pinion 94 on the shaft 93 engages and drives 35 a gear 95 on the cross shaft 54 which supports the crank arms 53.

The motor M is reversible and is controlled by 40 limit switches 97 and 98 (Fig. 4). When one of these switches 97 is closed, the motor M will be started and will partially revolve the gear 95 and crank arm 53 clockwise in Fig. 4 until an arm 99 on the gear 95 engages and opens the switch 97, thus stopping the motor. If the switch 98 is thereafter closed, a similar partial rotation in 45 the other direction will take place.

Pressure adjusting and equalizing devices

The pressure of the ironing members 31 and 32 against the main cylinder 30 and cloth C is 50 regulated by turning the cross rods 42 (Fig. 9) previously described. For convenient adjustment of these cross rods, I provide a worm shaft 100 having a separate worm 101 to engage the worm wheel 43 on each cross rod 42. A hand wheel 55 102 (Fig. 4) is mounted on the end of the worm shaft 100 and constitutes means for convenient manual adjustment of the distance between the pivot studs 37 of the ironing members 31 and 32.

In order to equalize the pressure between the 60 ironing members at both ends thereof, I make the worm shaft 100 in two parts, connected by a toothed clutch member 105 which may be slipped out of mesh to allow relative adjustment between the two parts of the shaft, thus adjusting one of 65 the worms 101 relative to the other.

I find it desirable to provide an indicating device to show the amount of adjustment of the ironing members toward or away from each other, and for this purpose I provide an index wheel 110 70 (Fig. 7) coacting with a fixed index 111 and connected with the worm shaft 100 by a worm gear 112, worm 113, worm shaft 114, sprocket 115, chain 116 and sprocket 117.

Suitable steam connections are provided for 75 heating the ironing members 31 and 32 and the

main cylinder 30. A steam supply pipe 120 (Fig. 4) is connected by branch pipes 121 and 122 to the rear ends of the ironing members 31 and 32 and is also connected by a pipe 124 (Figs. 4 and 6) through a swivel pressure connection and through 5 the cylinder journal 77 to the inside of the cylinder 30. A drainage pipe 125 is provided to remove condensation from the cylinder, and drainage pipes 126 (Fig. 4) are provided to remove condensation from the ironing members. 10

The preferred construction of the main cylinder is indicated in section in Fig. 8 and comprises a heavy steel drum 130 mounted between heads 131 supported by the shaft 76 and journal 77.

The detailed construction of the ironing members 31 and 32 is shown in Figs. 10, 11 and 12. Each ironing member is provided with bearing extensions 140, slideable on brackets 141 secured to the side frames 79 and 80, and held from displacement by caps 142. Each ironing member is 20 of hollow reinforced construction as shown in Fig. 12, and is provided with a highly polished copper facing 143. A guide or spreader member 144 is provided for the ironing member 31 and acts to guide and smooth the cloth as it approaches the cylinder 30.

Having described the details of construction of my improved rotary finishing press, the method of operation and advantages thereof will be readily apparent. After the cloth is threaded 30 through the machine, the lever 63 is moved to throw in the clutch and start the main cylinder 30 and brushes 24 and 25 in rotation. The motor M is then started, moving the gear 95 in the direction of the arrow a in Fig. 4, and thus moving 35 the rocking members 46 to the position shown in Figs. 4 and 9. This advances the ironing members 31 and 32 against the main cylinder 30 and the interposed cloth C with a pressure determined by the initial compression of the springs 49. 40

The floating bearings for the ironing members 31 and 32 and for the upright levers 36 permit the members 31 and 32 to adjust themselves to equalize pressure on the opposite sides of the cylinder 30, and the total pressure may be conveniently increased or decreased by use of the hand wheel 102 for angular adjustment of the right and left-hand threaded cross rods 42. 45

All parts of my improved rotary press are of strong and rugged construction and the press 50 may be operated at higher speeds and with greater pressures than have been heretofore considered practicable.

Having thus described my invention and the 55 advantages thereof, I do not wish to be limited to the details herein disclosed, otherwise than as set forth in the claims, but what I claim is:

1. In a rotary finishing press, a main cylinder, a pair of slidably mounted ironing members, levers connected to said members, floating pivot 60 bearings for said levers, means to rigidly connect the pivot bearings of opposed levers to permit only simultaneous movement thereof, means to force the ends of said opposed levers apart to apply pressure to said ironing members, and means to vary the pressure of the ironing members by changing the effective length of the rigid connection between the pivot bearings. 65

2. In a rotary finishing press, a main cylinder, 70 a pair of ironing members mounted at opposite sides of said cylinder, and means to apply pressure to said ironing members, said means including a rock shaft, link and lever connections from said rock shaft to said members, a crank 75

arm on said rock shaft, a cross shaft having a second crank arm, a link connecting said crank arms, and means to give said cross shaft partial angular movements in opposite directions.

5. 3. In a rotary finishing press, a main cylinder, a pair of ironing members mounted at opposite sides of said cylinder, means to apply pressure to said ironing members, said means including a rock shaft, link and lever connections from said 10 rock shaft to said members, a crank arm on said rock shaft, a cross shaft having a crank arm and a link connecting said crank arms, means to give said cross shaft partial angular movements in opposite directions, and means to stop 15 said cross shaft in predetermined angular positions.

4. In a rotary finishing press, a main cylinder, a pair of ironing members mounted for ironing engagement with said main cylinder at opposite 20 sides thereof, a single means to simultaneously apply pressure to both of said ironing members, a separate pressure-transmitting connection from said pressure-applying means to each of said ironing members, and devices effective to 25 produce equal simultaneous transverse bodily movements of said connections relative to said main cylinder but in opposite directions to equalize the pressure applied by said ironing members against said cylinder.

5. In a rotary finishing press, a main cylinder, a pair of ironing members mounted for ironing engagement with said main cylinder at opposite sides thereof, a single means to simultaneously apply pressure to both of said ironing members, 5 a separate pressure-transmitting connection from said pressure-applying means to each of said ironing members, and devices effective to produce a transverse bodily movement of one of said connections in one direction relative to said 10 main cylinder and a simultaneous and equal bodily movement of the other connection in the opposite direction relative to said main cylinder to equalize the pressure applied by said ironing members against said cylinder. 15

6. In a rotary finishing press, a main cylinder, a pair of slidably mounted ironing members, levers connected to said members, floating pivot bearings for said levers, means to rigidly connect the pivot bearings of opposed levers, and 20 means to force the ends of said opposed levers apart to apply pressure to said ironing members, said floating pivot bearings and said connecting means coacting to effect simultaneous transverse 25 equal but opposite bodily movements of said levers to equalize the pressure applied by said ironing members against said cylinder.

DAVID GEESNER.
